VENETIAN BLIND MOUNTING

Ralph T. Hendricks, Indianapolis, Ind., assignor
to Patterson Shade Co., Indianapolis, Ind., a
corporation of Indiana

Application February 24, 1936, Serial No. 65,259

6 Claims. (Cl. 156—17)

My invention relates to Venetian blinds, and more particularly to a releasable mounting for the header bar thereof.

It is the object of my invention to provide a simple, inexpensive, and reliable releasable mounting to support the header bar of a Venetian blind, so that such header bar and with it the Venetian blind as a whole may readily be removed and replaced, as for cleaning and assembling and repairing either the Venetian blind or the adjacent window or frame.

The accompanying drawing illustrates my invention. In such drawing: Fig. 1 is a front elevation of the upper part of a Venetian blind mounted in place in a window frame by mountings embodying my invention; Fig. 2 is a larger-scale longitudinal vertical section taken substantially on the lines 2—2 of Figs. 3 and 4, through the end of the header bar and mounting shown at the right in Fig. 1; Fig. 3 is a plan of the header-bar end and mounting of Fig. 2, with the supporting bracket shown in horizontal section; Fig. 4 is a transverse vertical section on the line 4—4 of Fig. 2; Fig. 5 is an isometric view of one form of supporting bracket, with the locking spring in normal locking position; and Fig. 6 is a similar isometric view of a slightly modified form of supporting bracket, with the locking spring pressed back into releasing position.

The Venetian blind per se may be of any conventional type having a header bar 10. That header bar is usually provided with a pair of depending brackets 11 between which is mounted a rockable top slat 12 from which a series of lower slats 13 is suspended by the usual ladder-tapes 14. The usual lifting cords 15 extend upward from the bottommost slat through holes in the slats above it into the header bar 10, and along such header bar over suitable pulleys 16 and conveniently through a suitable locking mechanism 17 near one end of the header bar and thence downward to a convenient point for manipulation. A suitable rocking cord 18 operates any convenient mechanism mounted on one of the brackets 11 to rock the top slat 12, and thereby through the action of the ladder tapes 14 to rock the other slats of the Venetian blind. All these may be of any conventional or desired construction.

Each end of the header bar 10 is releasably mounted in a supporting bracket 20, constructed in accordance with my invention. That supporting bracket 20 is shown in detail in Figs. 5 and 6. The type of bracket shown in Fig. 6 may readily be converted into the type shown in Fig. 5

by sawing off one end of the former, as will readily be apparent by comparing the two figures. Thus only one set of dies is necessary, and indeed only the type of bracket shown in Fig. 6 because it can so readily be connected into the other type. 5

The supporting brackets 20 are made of sheet metal. Each bracket has a vertical end-wall 21, which is in line with the header bar 10 and beyond its end; and a bottom horizontal flange or ledge 22 which projects from the lower edge of the vertical end-wall 21 and underlies and supports the header-bar end. Each bracket also desirably has a top horizontal flange 23, which projects from the upper edge of the vertical end-wall 21 and overlies the header-bar end and may serve as an 15 attaching flange. In addition, in the type of bracket shown in Fig. 6, the vertical end-wall 21 has an extension 24 toward the rear, and that extension is provided with a vertical flange 25 which may also serve as an attaching flange. It 20 is by omitting the extension 24 and vertical flange 25, or removing them as by sawing, that the type of bracket shown in Fig. 6 is converted into the type of bracket shown in Fig. 5.

The vertical end-wall 21, the top horizontal flange 23, and the vertical flange 25 are all desirably provided with holes 26 for receiving attaching screws 27, to permit the attachment of the bracket 20 to the associated frame 28, as of a window, by any of those parts as required by the 30 character of such frame; and the bottom horizontal flange 22 is desirably provided with holes 29 to permit the passage of a screw-driver for co-operation with the heads of any screws 27 that may be put through the holes 26 in the top horizontal flange 23. This permits a convenient mounting of the bracket in any of various types of frame 28, as conditions require. 35

Each bracket 20 is provided with a leaf-spring 30, which is suitably mounted at or near the top 40 of the vertical end-wall 21 on the inner face thereof and projects downward through an opening 31 in the bottom horizontal flange or ledge 22. The lower end of this leaf-spring is desirably provided with a thumb piece 32, of convenient 45 shape. The leaf-spring tends by its resilience to spring away from the vertical wall 21, into the locking position shown in Figs. 1, 2, 3, and 5; but may be pressed back against such end wall, as is shown in Fig. 6, by pressing against the thumb 50 piece 32.

Desirably the leaf-spring 30 enters a recess in the end-wall 21 when it is pressed back to the position shown in Fig. 6. That recess is conveniently provided by a filler plate 35 which is suitably fas- 55

tened, as by spot-welding 36, against the inner face of such end-wall 21 and is of a general inverted U-shape to provide that recess between its two legs. The cross-bar of that filler plate 35 may 5 serve to clamp the fixed end of the leaf-spring in place, as is clear from Fig. 2. The filler plate is conveniently provided with notches 37 around the screw-holes 26 in the vertical end-wall 21, to receive the screw-heads so that they will not project into the path of and interfere with the movement of the header bar 10 when the latter is put into or taken out of place.

Each end of the header bar 20 is provided with a vertical notch 40 for receiving the leaf-spring 15 30 when the latter springs into its normal position of Figs. 1, 2, 3, and 5. The notches 40 may be of any desired extent lengthwise of the header bar; such as the shallow notch 40 shown at the left-hand end in Fig. 1, or the deep notch 40 shown in Figs. 1, 2, and 3 at the right-hand end and also containing one of the pulleys 16 and the locking mechanism 17.

After the brackets 20 are mounted in place in the frame 28, such as a window frame, the complete Venetian blind as a unit may readily be slipped into place in said brackets, one end at a time if desired, by merely pressing back the leaf-springs 30 and sliding the header bar 10 into the two brackets 20. The header bar is held in place 25 30 in such brackets by the entry of the leaf-springs 30 of the two brackets 20 into the notches 40 when the header bar 10 is fully in place and said leaf-springs are released to spring to their normal position. To remove the Venetian blind, it is 35 merely necessary to press back the two leaf-springs 30, by pushing with the finger against their respective thumb-pieces 32, and then to slide the header bar forward out of the brackets 20.

40 I claim as my invention:

1. A Venetian-blind mounting, comprising a bracket adapted for mounting on a frame and having a ledge on which an end of a header bar of a Venetian blind rests, said header bar having an opening and a releasable spring mounted on said bracket and adapted by its resilience to enter the opening in the header bar.

45 2. A Venetian-blind mounting, comprising a bracket adapted for mounting on a frame and having an end-wall from a lower part of which projects a horizontal flange adapted to underlie and support an end of the header bar of a Venetian blind, said header bar having an opening,

and a leaf spring mounted on said end-wall and projecting through said flange into accessible position and adapted by its resilience to enter the opening in the header bar.

3. A Venetian-blind mounting, comprising a 5 bracket adapted for mounting on a frame and having an end-wall from a lower part of which projects a horizontal flange adapted to underlie and support an end of the header bar of a Venetian blind, said header bar having an opening, and a 10 leaf spring mounted on said end-wall and projecting into accessible position and adapted by its resilience to enter the opening in the header bar.

4. A Venetian-blind mounting, comprising a 15 bracket adapted for mounting on a frame and having an end-wall from which project upper and lower horizontal flanges between which an end of a header bar is adapted to lie, said lower flange and said header bar each having an opening, and a 20 leaf-spring mounted on said end-wall and projecting through the opening in the bottom flange into accessible position and adapted by its resilience to enter the opening in the header bar lying between said two flanges.

25 5. A Venetian-blind mounting, comprising a bracket adapted for mounting on a frame and having an end-wall from a lower part of which projects a horizontal flange adapted to underlie and support an end of the header bar of a Venetian blind, said header bar having an opening, and a 30 leaf spring mounted on said end-wall and projecting into accessible position and adapted by its resilience to enter the opening in the header bar resting on said ledge, said end-wall being 35 provided with a recess into which said leaf spring is received when it is pressed away from the header bar.

35 6. A Venetian-blind mounting, comprising a bracket adapted for mounting on a frame and 40 having an end-wall from which project upper and lower horizontal flanges between which an end of a header bar is adapted to lie, said lower flange and said header bar each having an opening, and a leaf-spring mounted on said end-wall 45 and projecting through the opening in the bottom flange into accessible position and adapted by its resilience to enter the opening in the header bar lying between said two flanges, said end-wall being 50 provided with a recess into which said leaf spring is received when it is pressed away from the header bar.

RALPH T. HENDRICKS.
